UNITED STATES PATENT OFFICE.

GEORGE W. T. HARLEY, OF FREDERICK, MARYLAND.

PAPER BOX.

SPECIFICATION forming part of Letters Patent No. 399,891, dated March 19, 1889.

Application filed January 10, 1889. Serial No. 295,926. (No model.)

To all whom it may concern:

Be it known that I, GEORGE W. T. HARLEY, a citizen of the United States, residing at Frederick, in the county of Frederick and State of Maryland, have invented certain new and useful Improvements in Paper Boxes; and I do hereby declare the following to be a full, clear, and exact description of the invention, such as will enable others skilled in the art to 10 which it appertains to make and use the same, having reference to the annexed drawings, forming a part of this my specification of said invention.

My invention relates to that class of paper boxes of thick stock, which, to economize room, are usually supplied to the market in a "flat" or "knockdown" condition, and which may be, at the convenience of the user, converted into box form by simply bending 15 up the sides and locking the same together by interlocking appliances provided at or near the ends of such sides.

In the drawings, Figure 1 represents the "blank," from which the body of a box or its 20 cover is made. Fig. 2 represents three sides or walls of the blank turned up and locked into a box position, it only requiring the remaining knocked-down wall shown in the figure to be turned up and locked to complete 25 the body of the box or its cover, as the case may be. Fig. 3 is a section in the line *x* of Fig. 2.

The paper blank shown "knocked down" in Fig. 1 is creased with a proper tool both longitudinally and transversely, as indicated in dotted lines, and so distinct lines of bend are formed for the four walls of the box, and also for the flaps formed on the opposite ends of 30 two of its walls.

40 A indicates the bottom of the box inclosed by the lines of the bend *a a'* and *b b'*. B B' are the side wall portions, and C C' the end wall portions of the blank. The end wall portions, C C', are each near their respective 45 ends provided with slits, as at *d*, cut through the blank, the length thereof being sufficient to receive the locking-tongue *d'* of a flap, F. (Shown at each end of the side wall portions, B and B'.) Midway of the length of these 50 slits *d* a portion of the stock of the end walls, C C', is cut away, so as to form an opening,

as at *e*, through the stock of the blank, such opening being in this instance somewhat in the likeness of the letter **D**, as shown, and forming at each of the ends of the side walls, 55 C C', one part of the locking device, which I employ for locking together the said walls B B' and C C' when they have been manipulated from their knockdown condition shown in Fig. 1 into the form of a box. The side wall 60 portions, B B', as shown in the figures, are made with end flaps, as at F. These flaps extend beyond or outside of the lines of bend *b* and *b'*, and are formed with tongue portions, as at *d'*, which are adapted to be thrust through 65 the slits *d* of the end wall portions, C C', in the act of locking the walls together. Each of these flaps F near the center thereof, as shown, has a circular-formed slit, as *g*, somewhat in the likeness of a letter **D** cut through 70 the flap, thus forming spring-like locking parts *e'* within said slits, which may, simply by pressure, be moved or sprung from one side to the other of the flap F. These locking parts 75 *e'* are precisely of such size as to fit snugly within the cut-away openings *e*, when the locking of the walls together is effected, as will presently be described. In Fig. 2 I have shown the side wall, B, turned up vertically 80 on its creased line *a*, with its flaps F F brought around against the vertically-turned-up end walls, C C', and with its locking-tongues *d'* respectively thrust through slits *d d* of the end walls. This thrust of the tongues *d' d'*, through said slits is shown to have been continued until the wall B has become vertical and until the extreme ends of the flaps F have impinged against the bottom A of the box, or shall have been thrust far enough toward the bottom A to bring the spring-like locking 85 parts *e'* of said flaps F into exact register with openings *e* of the end walls, C C', at which moment the operator, by pressing the locking parts *e'* out from their slits *g* of the flaps F into openings *e* of the said walls C C', effects 90 the locking together of the walls B, C, and C'. By thus locking the parts in juxtaposition it will be seen that a pull applied to withdraw the flaps and release the wall B from its position shown in Fig. 2 will be resisted by 95 the contact of the locking parts *e'* against the end walls, C C', while thus seated in the open-

ings *e* of said end walls; but by simply applying pressure against the parts *e'*, so as to force them out of their seats in the openings *e* and back into their normal positions within the 5 slits *g* of said flaps, the flaps may at once be withdrawn from the slits *d d* of the end walls and the walls *B C C'* turned down from their position shown in Fig. 2 to their flat or level position shown in Fig. 1. Having locked the 10 wall *B*, for example, to the respective ends of the end walls, *C C'*, as shown in Fig. 2, the wall *B'* may now by the same manipulation be locked to the opposite ends of the end walls, thus completely converting the blank 15 shown in Fig 1 into a box. It is apparent that the cover of a box, as well as its body portion, may be made as above described, the cover being of course made of somewhat greater

area than the body it is to fit upon. Stops, as *m*, cut in the side walls, *B B'*, and turned 20 down, as shown, serve to stay the end walls, *C C'*, in position, as shown in Fig. 2.

I claim—

A paper box which comprises in its construction one or more walls having end flaps, 25 *F*, provided with locking parts *e'*, in combination with one or more walls provided with a slit, *d*, and an opening, *e*, substantially as and for the purpose described.

In testimony whereof I hereunto affix my 30 signature in presence of two witnesses.

GEORGE W. T. HARLEY.
